United States Patent Office.

OSCAR GOERKE, OF BROOKLYN, NEW YORK.

Letters Patent No. 72,480, dated December 24, 1867.

IMPROVEMENT IN STEREOSCOPES.

The Schedule referred to in these Letters Patent and making part of the same.

TO ALL WHOM IT MAY CONCERN:

Be it known that I, OSCAR GOERKE, of Brooklyn, in the county of Kings, and State of New York, have invented a new and useful Improvement in Stereoscopes; and I do hereby declare that the following is a full, clear, and exact description thereof, which will enable others skilled in the art to make and use the same, reference being had to the accompanying drawings, forming part of this specification.

Figure 1 is a horizontal section of my improved stereoscope, taken through the line *x x*, fig. 2.

Figure 2 is a vertical section of the same, taken through the line *y y*, fig. 1.

Similar letters of reference indicate corresponding parts.

My invention has for its object to simplify and improve the construction of stereoscopes, so as to make them less expensive in construction, and more effective and convenient in operation; and it consists in the construction of the picture-holders, in the construction of the upper cylinder or shaft, and in the combination of parts, by which the bearings for the lower cylinder or shaft are adjusted to tighten or loosen the endless belt, as required, the whole being constructed and arranged as hereinafter more fully described.

A is the box, which is made upright, and the top of which is hinged, so as to open in the ordinary manner. The box *A* is made open at the bottom, so that, should any of the pictures accidentally fall into it, they can be readily removed. *B* is an endless belt, which I prefer to make of rubber, to which the picture-holders *C* are attached, and which passes around the shafts or cylinders *D* and *E*. The picture-holders *C* are formed by attaching the end wires *c'*, the upper ends of which are bent, so as to form a horizontal loop for the reception of the ends of the pictures, and the central straight wire or pin *c''*, to the stick or bar *c''*, which is attached to the endless belt or belts *B*, and which are made much smaller and lighter than can be done when the machine is constructed in the ordinary manner, allowing a much larger number of pictures to be inserted than can usually be done. The upper shaft or cylinder *D* is made octagonal in shape, and much smaller than in the common machines, thus getting rid of the projecting corners or angles of the ordinary shaft, and allowing the pictures to stand closer together than they otherwise could. The size of the lower shaft *E* is immaterial, but, by increasing its size, the length of the endless belt or belts will be increased, and, consequently, the number of pictures that may be used. The journals of the shaft or cylinder *E* revolve in slots or bearings in the sliding bars *F*, which slide up and down along the sides of the box *A*, and are kept in place by the flanges or keepers *G*, attached to said sides of the box, and which form grooves to receive the ends of the said bars. *H* are cords, the ends of which are connected to the sliding bars *F*, near their ends, and which are attached to the set-screws *I*, so that, by turning the said screws in one or the other direction, the endless belt or belts *B* may be tightened or slackened, as may be desired.

I claim as new, and desire to secure by Letters Patent—

1. The picture-holders *C*, constructed as described, consisting of the end wires *c'*, in the bars *c''*, their upper ends bent to form a horizontal loop for the ends of the pictures, and the central pin *c''*, as herein shown and described.
2. The construction of the octagonal rollers *D E*, endless belt *B*, picture-holders *C*, sliding bar *F*, guides *G*, cord *H*, and pin *I*, all arranged and operating as herein described for the purpose specified.
3. The combination of the set or adjusting-screws *I*, cords *H*, sliding bars *F*, and flanges or keepers *G*, with each other, and with the shaft or cylinder *E* and box *A*, substantially as herein shown and described, and for the purpose set forth.

OSCAR GOERKE.
